(57) **CLAIM**

The ornamental design for a display container, as shown and described.

DESCRIPTION

FIG. 1 is a perspective view of a first embodiment of a display container, showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof; and

FIG. 8 is another perspective view thereof.

FIG. 9 is a perspective view of a second embodiment of a display container, showing my new design;

FIG. 10 is a front elevation view thereof;

FIG. 11 is a right side elevation view thereof;

FIG. 12 is a left side elevation view thereof;

FIG. 13 is a rear elevation view thereof;

FIG. 14 is a top plan view thereof;

FIG. 15 is a bottom plan view thereof; and,

FIG. 16 is another perspective view thereof.

Dashed lines are included for the purpose of illustrating use and environment and form no part of the claimed design.

1 Claim, 8 Drawing Sheets
